UNITED STATES PATENT OFFICE.

GEORGE W. McFARLAND, OF DAYTON, OHIO.

WINDOW-SCREEN.

No. 823,737.

Specification of Letters Patent.

Patented June 19, 1906.

Application filed December 1, 1905. Serial No. 289,718.

To all whom it may concern:

Be it known that I, GEORGE W. McFARLAND, a citizen of the United States, residing at Dayton, (address Lock Box 478,) in the county of Montgomery and State of Ohio, have invented certain new and useful Improvements in Window-Screens; and I do hereby declare that the following is a full, clear, and exact description of the invention, which will enable others skilled in the art to which it appertains to make and use the same, reference being had to the accompanying drawings, and to the characters of reference marked thereon, which form a part of this specification.

My invention relates to improvements in window-screens, the features of which will be fully hereinafter described and claimed.

The object of my invention is to connect the wire-cloth to the frame in a convenient and substantial manner and so that the same can be detached when required.

The mechanical construction is illustrated in the accompanying drawings, in which—

Figure 1 is a front elevation of the improved screen. Fig. 2 is an enlarged transverse section of one side of the frame.

Like letters and numerals designate like parts throughout both views.

The frame A is of metal and is provided with the deep groove 1 throughout the length of the sides and the top and bottom. This

groove inclines very slightly, giving greater width at the bottom. The small tubes B, having extensions equal to the sides of the frame, are adapted to be forced into said grooves. These light tubes are cut through, as shown at 2, Fig. 2, thus forming a longitudinal slot the full length, and thus are rendered slightly compressible. The operation of attachment is to place the wire-cloth over the frame and then press the tubing or spline over the grooves until the cloth is carried fully into said grooves. The resiliency of the metal makes the holding secure against the inclined sides of the groove.

To release the wire-cloth, it is only necessary to lift the splines out of position.

Having fully described my invention, what I claim is—

In an improved window-screen the combination of the frame with groove enlarged inwardly, the resilient slotted tubes forming a filling-piece adapted to be inserted in said groove, the wire fabric to be engaged therein, substantially as described.

In testimony that I claim the foregoing as my own I affix my signature in presence of two witnesses.

GEORGE W. McFARLAND.
